ARTHUR E. READ, OF NEW YORK, N. Y.

ELECTRIC SWITCH.

1,280,547.

Specification of Letters Patent.

Patented Oct. 1, 1918.

Application filed July 21, 1917. Serial No. 181,955.

To all whom it may concern:

Be it known that I, ARTHUR E. READ, a citizen of the United States, and a resident of the borough of Manhattan, city, 5 county, and State of New York, have invented certain new and useful Improvements in Electric Switches, of which the following is a specification.

The main object of my invention is the 10 production of a simple, compact, inexpensive but durable and efficient electric switch of the one-push-button type,—one in which electrical contact is made and broken instantaneously with a snap which obviates 15 sparking and injury to the terminals, the burning out of terminals being the main cause of defect and failure in most electrical switches of this class.

The invention consists in the specific construction and arrangement of parts described and claimed,—distinctive features being the shape of the base core and the formation and assembling of the several operative parts as hereinafter fully set forth.

25 In the accompanying drawings, for convenience of illustration, the parts are shown on a scale approximately twice as large as the model, or as made for commercial purposes. In other words the actual device occupies only one-fourth of the space indicated in the drawings, so as to adapt it for 30 use on automobiles and other situations where available space is restricted to a minimum.

35 Figure 1, is a sectional elevation showing my electric switch installed on a suitable fixed support;

Fig. 2, is a perspective view of the internal operative parts with the casing and 40 push button indicated in dotted lines, and the core or base broken away and in partial section;

Fig. 3, is an elevation of the base core without the shell and showing the ends of 45 the duplex spring terminal as broken away and the circuit closer blade in "open" position;

Fig. 4, is a transverse section taken upon plane of line 4—4, Figs. 1, and 3;

50 Fig. 5, is a perspective view of the rotatable circuit closer;

Fig. 6, is a perspective view of the spring pawl member by which the rotatable circuit closer is actuated;

55 Fig. 7, is a transverse section of the shank

of said spring pawl, taken on the line indicated by the arrow 7, Fig. 6;

Fig. 8, is a perspective view of the other or bifurcated terminal;

Fig. 9, is a perspective view of the push 60 button;

Fig. 10, is a diagrammatic view illustrating the operation of the rotatable contact member or circuit closer.

Fig. 11, is an elevation of the base-core 65 broken away medially, and taken at right angles to Fig. 3.

The base core B, is essentially cylindrical in general configuration, being formed with a central compartment b, in which the 70 terminals C, C', and rotatable circuit closer D, are positioned, and with an annular shoulder b', against which the inner edge s, of the shell S, abuts, and also with a transverse base flange or partition b², which acts 75 as a barrier between the terminal connections to prevent accidental cross-circuiting, etc. That is to say the flange b², prevents a metallic tool or other extraneous metallic body from contacting with both 80 binding screws c, c, at the same time. The shoulder b', is the same width as the thickness of the shell S, so that the joint between the latter and the base core B, is flush externally. The base core B, is made of any 85 desired nonconductive material, and is of such simple form that it may be conveniently molded or cast in quantities at relatively small cost,—its configuration adapting it to being readily drawn from the matrix, and 90 calling for little or no "finishing".

To the floor of the compartment b, of the base core B, are secured the circuit terminals C, C', by means of binding screws c, c, passing through the base core as shown in 95 Fig. 1, said binding screws c, c, being secured in turn by binding nuts c', c', and lock nuts c², c². Of these, the binding nuts c', c', are preferably countersunk in the base core B, so as to bring their outer sides substantially flush with the outer end surface of said base core, thereby economizing space 100 and protecting the binding nuts in their permanent setting against disturbance when, for instance, the terminal wires c³, c⁴, 105 are inserted and clamped between said binding nuts c', c', and the lock nuts c², c², which insure an electrical contact between the parts.

As will be seen by reference more par- 110

ticularly to Fig. 2, the duplex circuit terminal C, is formed of a single piece of sheet metal bent over upon itself to form the medial base c⁶, with the opposed twin-spring jaws c⁶, the free ends of which tend constantly to contact with each other,—the extremities of said free ends of the twin jaws being flared or bent outward away from each other slightly to facilitate the intrusion between them of the circuit closer blade d, into the position shown in Figs. 1 and 2.

The other or bifurcated circuit terminal C', is also formed of a strip of sheet metal bent up to constitute the base c⁷, and the twin springs c⁸, the latter formed by the creation of the slot c⁹, between them for the accommodation of the circuit closer blade d, with which however, they do not contact but merely straddle when said circuit closer blade d, is in the position shown in solid lines in Figs. 1, and 2.

The rotatable circuit closer D, consists of the bridge or contact blade d, and the ratchets d', d', secured thereto, one on each side thereof. The ratchets d', d', as well as the circuit closing blade d, are of metal, and each has four apices or teeth d², coincident respectively, in the construction shown, with the longitudinal edges of the circuit closer blade d, although this is not a material feature. The ratchets d', d', constitute essentially the hub of the rotatable circuit closer D, and said hub being four-sided for engagement with the bifurcated spring terminal C', which also performs the function of a detent to hold said rotatable circuit closer D, stationary except when partially rotated by the depression of the spring pawl E.

The axial pin d³, on which the circuit closer rotates is supported in the side walls of the compartment b, of the base-core B, and also serves to secure the ends of the straps e, e, which straps form the base of the spring pawl E, and are seated in a groove b², formed for them in the base-core B, as shown particularly in Figs. 3, and 4, the side walls of the groove confining the straps e, e, between them so as to sustain the base of the spring pawl E, against displacement when the free end of the latter is depressed to operate the rotatable circuit closer D.

The free end e', of the spring pawl E, is bifurcated to straddle the bridge blade d, of the rotatable circuit closer D, and the portion of the spring E, intermediate between said free end e', and its basic straps e, e, is bent not only to form what may be designated as the shank e², but also to form a bearing and support e³, for the inner side of the push button P. The base core B, adjacent to the shank e², of the spring pawl E, is beveled off (as at b³, Figs. 1, 2, and 11) to admit of the free play of said shank e², when

the spring pawl E, is depressed to turn the circuit closer D.

The outer end of the casing S, supports the push button P, against the thrust of the spring pawl E, and is formed with the opening s', for the protrusion of the finger bearing p, of said push button P. The flange or body p', snugly fits the interior of the casing S. S', is a flat escutcheon plate that may be attached to the shield S, by a drive-fit to stabilize the device laterally and afford a finished external appearance, although this plate forms no part of my invention and may be omitted where available space is limited.

In order to economize space as much as possible, and reduce the diameter of the device to a minimum, I form the shank e², of the spring pawl E, with a recess e²¹, to accommodate the ends of the closure blade d, when the latter is in either of its transverse positions as shown more particularly in Fig. 4. The depression of the spring pawl E, is limited by the contact of its shoulders e⁴, e⁴, with shoulders b⁴, b⁴, on the base-core B. This prescribed inward thrust of the bifurcated free end e', of the spring pawl E, is just sufficient to carry the teeth d², d², of the ratchets d', d', with which it is engaged only slightly beyond the axis d³, of the rotatable circuit closer D, or over the dead center, when the spring terminal C', completes the one fourth rotation of the circuit closer, forcing it over until it contacts with the next succeeding flat sides of the ratchets d', d'. This action is exemplified diagrammatically in Fig. 10, in which the result of the thrust of the spring pawl E, is illustrated in dotted lines, and the completion of the quarter turn of the circuit closer is shown in solid lines, this being the normal position of the spring terminal C', as related to the ratchets d', d'. In other words, the spring pawl E, turns the circuit closer D, over, say 46° and the spring terminal forces or "snaps" it over the other 44° as indicated in said diagram Fig. 10. Thus a relatively short stroke of the spring pawl E, is sufficient to insure a quick "make" or "break" of the electrical circuit by means of the rotatable contact blade d,—the sudden (practically instantaneous) opening or closure of the circuit effected by the spring terminal C', effectually preventing "sparking" and consequent burning out of contacts.

To insure positive insulation of the operative parts contained within the casing S, I provide the latter with an internal lining s², interposed between said casing S, and the main portion of the base core B, as shown in Fig. 1, which prevents all possibility of short circuiting with said casing, or grounding therethrough.

Advantages attained by my construction

and arrangement of parts are, simplicity, cheapness, compactness, durability and safety or longevity of service. The parts are comparatively few and easily made, and may be 5 assembled by unskilled labor at a minimum of cost and time. Furthermore the terminals, spring pawl, rotatable circuit closer, etc., may be stamped out from sheet metal; while the base-core may be conveniently 10 molded and drawn in such quantities as to reduce the cost to a fraction of a cent apiece. And the internal side walls of the work compartment in the base core insulate and protect the operative parts and preserve 15 their alignment and correlation.

As designed for the trade, the barrel or casing S, is only, say, three fourths of an inch in diameter, so that in installing the device for instance on the dash or instrument 20 board of an automobile, it is only necessary to drill a scant three fourths inch hole and then forcibly insert the barrel therein,—the escutcheon S', being used or omitted according to circumstances and conditions,— 25 whereas in the case of ordinary switches of this class on the market the casing is usually square or oblong, necessitating the making of a square hole or recess which requires the skill of a carpenter or some one familiar with the use of tools.

What I claim as my invention and desire to secure by Letters Patent is,

1. An electric switch of the character designated, comprising a base-core of non-conducting material formed with a transverse central compartment, and with a medial peripheral groove, circuit terminals positioned in said central compartment, a rotatable circuit closer pivotally supported in and between the side walls of said compartment and between said terminals, a spring pawl, formed with base bands countersunk in said medial peripheral groove of the base-core and arranged to actuate said rotatable circuit closer, a push button contacting with said spring pawl, and a casing inclosing the said base core and operative parts and limiting the outward thrust of the push button, for the purpose described.

50 2. An electric switch of the character designated, comprising a base-core of non-conducting material formed with a transverse central compartment, and with a medial peripheral groove, circuit terminals positioned in said central compartment, a rotatable circuit closer pivotally supported in and between the side walls of said compartment and between said terminals, a spring pawl formed with base bands countersunk in said 55 medial peripheral groove of the base-core and arranged to actuate said rotatable circuit closer, a push button contacting with said spring pawl, and a casing inclosing the said base-core and operative parts and limit-

ing the outward thrust of the push button, 65 said base-core being also recessed adjacent to said medial peripheral groove to accommodate the shank of the said spring pawl, for the purpose described.

3. An electric switch of the character designated, comprising a base-core of non-conducting material formed with a transverse central compartment, and with a medial peripheral groove, circuit terminals positioned in said central compartment, a rotatable circuit closer pivotally supported in and between the side walls of said compartment and between said terminals, a spring pawl formed with base bands countersunk in said medial peripheral groove of the base-core 70 and arranged to actuate said rotatable circuit closer, a pin extending diametrically through said core and securing the ends of the base bands of said spring pawl and forming the fulcrum for said rotatable circuit 75 closer, a push button contacting with said spring pawl, and a casing inclosing the said base core and operative parts and limiting the outward thrust of the push button, for the purpose described.

4. An electric switch of the character designated, comprising a base-core of non-conducting material formed with a transverse central compartment, circuit terminals positioned therein, a rotatable circuit closer pivotally supported in and between the side walls of said compartment and between said terminals, said circuit closer consisting of a contact blade with hub ratchets on either side thereof, a spring pawl arranged to actuate said rotatable circuit closer and formed with a bifurcated free end adapted to straddle said contact blade, a push button contacting with said spring pawl, and a casing inclosing the said base-core and operative parts and limiting the outward thrust of the push button, for the purpose described.

5. An electric switch of the character designated, comprising a base-core of non-conducting material formed with a transverse central compartment, circuit terminals positioned therein, a rotatable circuit closer pivotally supported in and between the side walls of said compartment and between said terminals, said circuit closer consisting of a contact blade with hub ratchets on either side thereof, a spring pawl arranged to actuate said rotatable circuit closer and formed with a bifurcated free end adapted to straddle said contact blade, and also 110 formed with a recessed shank to accommodate said contact blade, a push button contacting with said spring pawl, and a casing inclosing the said base-core and operative parts and limiting the outward thrust of the push button, for the purpose described.

6. An electric switch of the character designated, comprising a base-core of non-

conducting material formed with a transverse central compartment, circuit terminals positioned therein, one consisting of a strip of sheet metal bent up to form opposed 5 twin spring jaws and the other consisting of a bent strip of sheet metal formed with a bifurcated free end, a rotatable circuit closer pivotally supported in and between the side walls of said compartment and between 10 said terminals, a spring pawl arranged to actuate said rotatable circuit closer, a push button contacting with said spring pawl, and a casing inclosing the said base-core and operative parts, and limiting 15 the outward thrust of the push button.

7. An electric switch of the character designated, comprising a base-core of non-conducting material formed with a transverse central compartment, circuit terminals 20 positioned therein, one consisting of a bifurcated detent spring, a circuit closer pivotally supported in and between the side walls of said compartment and between said terminals, said circuit closer consisting of a 25 contact blade with hub ratchets on either side thereof, against which said bifurcated

terminal detent spring contacts, a spring pawl arranged to contact with said ratchet and actuate the circuit closer, and means for limiting the inward thrust of said spring 30 pawl, for the purpose described.

8. An electric switch of the character designated, comprising a rotatable circuit closer consisting of a pivoted contact blade formed with side hub ratchets, terminals 35 positioned to engage with said contact blade, one terminal in the form of a bifurcated spring detent contacting with said hub ratchets, a spring pawl engaging said hub ratchets and adapted to actuate the rotatable circuit closer, and means for stopping the inward thrust of said spring pawl after it has turned said rotatable circuit closer beyond 45° , so that said bifurcated spring detent terminal will instantaneously 40 open or close the electric circuit with a "snap" movement and thereby prevent 45 sparking, for the purpose set forth.
